W. J. THUL.

AUTOMOBILE HEADLIGHT DIFFUSER AND DEFLECTOR.

APPLICATION FILED NOV. 5, 1915.

1,250,714.

Patented Dec. 18, 1917.

William J. Thul Inventor

Robert E. Fuller

UNITED STATES PATENT OFFICE.

WILLIAM J. THUL, OF MELROSE, MINNESOTA.

AUTOMOBILE-HEADLIGHT DIFFUSER AND DEFLECTOR.

1,250,714.

Specification of Letters Patent. Patented Dec. 18, 1917.

Application filed November 5, 1915. Serial No. 59,875.

To all whom it may concern:

Be it known that WILLIAM J. THUL, a citizen of the United States, and resident of Melrose, in the county of Stearns and State 5 of Minnesota, has invented certain new and useful Improvement in Automobile-Head-Light Diffusers and Deflectors, of which the following is a specification.

This invention relates to automobile head-light diffusers and deflectors, and one of the 10 principal objects of the invention is to provide, reliable and efficient means for preventing the glare of the light from blinding the sight of pedestrians.

Another object of the invention is to 15 provide a head-light diffuser for automobiles in which the light is deflected downward without changing the construction or operation of the light or the reflector.

Still another object of the invention is to 20 provide a headlight deflector, preferably of flexible semitransparent material such as celluloid, ground on one side, and which is adapted to be fitted over the glass opening of 25 the head-light.

These and other objects may be obtained in the accompanying drawing, in which,

Figure 1 is a front view of an automobile headlight with the diffuser attached thereto.

Fig. 2 is an end view of the diffuser.

Like reference characters represent like 30 parts throughout the several views.

Referring to the drawing, the numeral 3 denotes the outermost portion of the head-light reflector and which contains a number 35 of fastening pins 4. It will be readily understood that this reflector is concave and tends to project the light rays directly forward, thereby making it difficult for the

operators of approaching vehicles to see the oncoming vehicle or the roadway over which 40 they are traveling. To obviate this intense glare from the head-light reflector and incidentally to deflect a sufficient portion of the

45 light rays in a downward direction so that the roadway may be more clearly distinguished, I provide a celluloid disk 5 having a number of notches 6 on its edge, the disk being adapted to lie flat against the

50 glass pane of the head-light, the pins 4 fitting into the notches 6, thereby holding same against ordinary removal. The disk 5 may

also be made slightly larger than the inner diameter of the reflector ring, the disk 5 then fitting frictionally between the glass pane 55 and the reflector ring 3 as shown by the dotted lines.

The disk 5 is ground on one side as indicated by the numeral 7. This has the effect of diffusing the light rays as projected from 60 the reflector and eliminates the glare. In order to deflect some of the light rays where they are most needed, namely in a downward direction in order to illuminate the road-way, immediately in front of the vehicle, I provide a series of vanes 8 as shown.

As will be readily apparent, these vanes are simply pressed outward at an angle from the disk so that portion of the light which would otherwise be reflected backward from the disk, the ground portion 7 acting also as a partial reflector, is now utilized in a very effective manner without materially affecting the volume of light diffused by the apparatus.

From the foregoing it will be obvious that 75 head-light diffuser made in accordance with this invention is extremely simple in construction, will prevent the intense glare so common with a sufficient portion of the light rays on the roadway directly in front of the vehicle, can be manufactured at a low cost, is very simple and easy to attach or detach while it will afford to the head-light a neat and elegant appearance.

80 Various changes may be made in the details of construction without departing from the spirit and scope of the invention as defined in the claims.

85 What is claimed is:—

1. A headlight dimmer comprising a celluloid disk ground on the outside so that the disk is light diffusing, and a series of angularly disposed vanes, each vane formed by cutting the disk transversely in a horizontal 95 line and pressing this part outwardly, and so spaced from the adjacent vanes that a flat, diffusing and reflecting portion is interposed between each pair of vanes of the series.

2. A headlight dimmer comprising a celluloid disk ground on the outside so that the disk is light diffusing, and a series of angularly disposed vanes, each vane formed by

cutting the disk transversely in a horizontal line and vertically at each end and pressing this part outwardly, and so spaced from the adjacent vanes that a flat diffusing and reflecting portion is inter-posed between each pair of vanes of the series.

5 Signed at the city of Melrose in the county

of Stearns and State of Minnesota this 2nd day of November A. D. 1915.

WILLIAM J. THUL.
